Primary Examiner—Doris Clark

(74) Attorney, Agent, or Firm: Roberts Abokhair & Mardula LLC

(73) Assignee: **Compass Group USA, Inc.**, Charlotte, NC (US)

(57) CLAIM

The ornamental design for an environmental enclosure for vending machines, as shown and described.

(**) Term: **14 Years**

DESCRIPTION

(21) Appl. No.: **29/133,490**

FIG. 1 is a front view of an environmental enclosure for vending machines showing our new design;

(22) Filed: **Nov. 30, 2000**

FIG. 2 is a top plan view thereof;

(51) LOC (7) Cl. **25-03**

FIG. 3 is a left side elevational view thereof, the right side being a mirror image.

(52) U.S. Cl. **D25/58; D25/4**

The rear of the environmental enclosure for vending machines forms no part of the claimed design.

(58) Field of Search D25/58, 4; 52/36.1
